Marcel Christen, New York, N. Y.

Application January 9, 1939, Serial No. 82,252

Term of patent 3½ years

To all whom it may concern:

Be it known that I, Marcel Christen, a citizen of the United States, residing in the Borough of Bronx, city of New York, county of Bronx, and State of New York, have invented a new, original, and ornamental Design for a Textile Fabric or Similar Article, of which the following is a specification, reference being had to the accompanying drawing, forming part thereof.

The drawing is a plan view of a textile fabric or similar article showing my new design.

The design consists of a series of rope-like elements of contrasting color extending in substantially parallel lines along a background of another contrasting color, the lighter spots in said rope-like elements being of a lighter shade but of the same color as the ground coloration of said rope-like elements.

I claim:

The ornamental design for a textile fabric or similar article, as shown and described.

MARCEL CHRISTEN.
